CLAIM

The ornamental design for a beverage dispensing container or similar article, as shown and described.

DESCRIPTION

FIG. 1 is a perspective view of a beverage dispensing container embodying my new design;

FIG. 2 is a front view of the beverage dispensing container of FIG. 1;

FIG. 3 is a side view of the beverage dispensing container of FIG. 1 with the other side view thereof being substantially the same;

FIG. 4 is a rear view of the beverage dispensing container of FIG. 1; and

FIG. 5 is a side view of the beverage dispensing container of FIG. 1 which has an outer shell portion thereof bisected on a vertical plane through the central longitudinal axis of the container and showing such shell in cross section.

The design is characterized by a sleeve which completely envelops the container and which has a flattened bottom portion which extends from the very front of a collar-like extension in front to the very rear thereof which envelops a convex end of the container.
